UNITED STATES PATENT OFFICE.

ERNEST G. GOODWIN, OF BROOKLYN, NEW YORK, ASSIGNOR TO STANDARD COUPLER CO., OF NEW YORK, N. Y., A CORPORATION OF NEW JERSEY.

FRICITION DRAFT GEAR.

Application filed January 5, 1922. Serial No. 527,066.

This invention relates to draft gears and, more particularly, in some of its more important features to that type of apparatus commonly known as friction draft gears 5 particularly adapted and designed for use in connection with railway cars.

A general object of the invention is to improve and perfect draft gears of the class mentioned whereby the same functions more satisfactorily in use, and more effectively 10 withstands the shocks and stresses incident to severe usage to which apparatus of this class is subjected in service.

Another object of the invention is to provide improved construction for draft gears 15 of the class mentioned, whereby it is possible to employ springs of increased length and capacity without increasing the over-all dimensions of the gear assembly.

Still another object is to provide a draft gear of improved and sturdy construction and capable of assembly into an operative self-contained and self-sustaining portable unit which is easily transported from place 25 to place and applied in operative position on a car or removed therefrom without use of special tools or apparatus.

Another object of the invention is to provide a draft gear of the friction type having 30 a spring barrel with reinforcements of improved design combining to brace and strengthen the structure so as to withstand shocks and stresses incident to hard usage while, at the same time, keeping the gear 35 well within the dimensional limits fixed by standard practice.

Other objects will be in part obvious in connection with the accompanying detailed description and in part pointed out in connection therewith.

The invention accordingly comprises the features of construction combinations of elements, and arrangement of parts, which will be exemplified in the constructions herein- 45 after set forth and the scope of the application of which will be indicated in the claims.

In the accompanying drawings wherein an illustrative but preferred embodiment of the invention is shown,

Figure 1 is a side elevation of a friction draft gear unit constructed in accordance with this invention;

Fig. 2 is a top plan view thereof;

Fig. 3 is a front elevation of the spring

barrel with the springs and other operative 55 parts removed therefrom;

Fig. 4 is a longitudinal section through the draft gear unit taken approximately on the line 4—4 of Fig. 3, looking in the direction of the arrows;

Fig. 5 is a transverse composite section taken approximately on the line 5—5 of Fig. 2, looking in the direction of the arrows;

Fig. 6 is a transverse section on the line 65 6—6 of Fig. 1 looking in the direction of the arrows;

Fig. 7 is a detail plan view of one of the side friction blocks; and

Fig. 8 is a detail front elevational view of 70 the friction box.

Referring to the drawing for a detailed description of the embodiment of the invention shown, the principal operative elements of the draft gear include a spring barrel A, 75 a friction box B, secured to the forward end or mouth of the spring barrel, a center friction block C against which are seated the draft springs housed within the spring barrel, additional or side friction blocks D arranged frictionally to engage the friction box and the center friction block, and a follower plate E arranged frictionally to engage the friction blocks D.

The spring barrel A is preferably of integral cast construction having exterior top and bottom walls 10, lateral side walls 11, and a bottom or rear wall 12, co-operating to provide an elongated box or barrel substantially rectangular in cross section. Extending between the opposed external walls of the spring barrel are interior joined walls 13, 14, 15, and 16, which are joined also with the side walls and the top and bottom walls. Certain of these walls may be curved, as 95 clearly shown in Figs. 5 and 6, to form longitudinally extending tubular columns arranged at the longitudinal corners of the barrel, each column forming a compartment for receiving and housing the draft gear 100 springs. These columns also function to reinforce the barrel longitudinally thereof, and the interior walls also provide lateral reinforcements for the barrel. In addition to the interior walls mentioned, there are 105 interior walls 17 and 18 inwardly spaced from the respective planes of the top and bottom walls near the inner end of the

spring barrel and inclining outwardly toward the outer end thereof as at 17' and 18' respectively. The walls 17 and 18, at their forward portions merge into wall sections 19 and 20 lying approximately in the planes of the respective top and bottom walls, and also merging with and forming parts of the latter. Spaced outwardly from the rear end portions of the walls 17 and 18 are relatively short external walls or flanges 21 and 22, united at their lateral edges with the top and bottom walls and co-operating with the walls 13, 14, 17 and 18, to provide short additional longitudinal tubular columns for providing additional reinforcement of the barrel at its rear or inner end where shocks and stresses are particularly severe. For further increasing the strength and rigidity of the rear end of the spring barrel, as clearly shown in Figs. 4 and 6, certain of the walls, for example, the walls 13, 14, 15 and 16, may be constructed extra thick and heavy adjacent the bottom 12, tapering off gradually toward their forward extremities. The walls 13 and 14 also co-operate with walls 17 and 18 in the vicinity of the bottom wall 12 to provide another and centrally arranged longitudinal reinforcing column, an additional function of which is to provide a compartment for a central draft spring, walls to reinforce barrel construction.

Draft springs are housed within the corner columns and are preferably of the helical type including inner and outer coils 23 and 24, wound in opposite directions. The centrally arranged spring is of similar construction in having inner and outer coils 25 and 26. Suitable formations, including lugs 27 are arranged in the base of the barrel for providing suitable seats for the respective springs. Also apertures 28 may be formed in the exterior of the walls of the spring barrel, furnishing ventilating and drainage openings for the interior of the barrel and permitting inspection and adjustment of the springs.

The forward end of the spring barrel is reinforced by a thickening or bulb flange 29, surrounding the edge of the external walls, and upon this flange is seated the friction box B, having a peripheral groove for receiving said flange. When the parts have been assembled and the friction box is seated in position at the mouth of the spring barrel, holes are drilled, as indicated at 30, extending over the adjacent faces and spanning the space between the friction box and spring barrel. These holes are disposed only at diagonally opposite corners of the friction box, being drilled from the outside of the latter and terminating short of the opposite surface of the friction box. A rivet or key 31 is driven while hot into the hole 30, and forced tightly therein against

the sides and bottom walls thereof, so as to cause the hot metal to flow to some extent from the sides and inner end thereof, as indicated at 32. Since the key aperture through the outer wall of the spring barrel is circular this rib of metal provides an internal securing bead or extension which cannot be withdrawn through said aperture. This construction locks the key rigidly in securing position avoiding accidental removal and insuring a firm union between the friction box and spring barrel not likely to get loose under severe conditions of service.

The friction box is formed with inclined friction surfaces 33, and opposed thereto are corresponding oppositely inclined friction surfaces of the center friction block C, thus forming a V-shaped friction socket for receiving and co-operating with the friction surfaces of the side friction blocks D which are formed to seat in contacting position with the respective friction walls of the central friction block and friction box. As shown in Figs. 4 and 8, friction surfaces 33 may be crowned or curved outwardly slightly intermediate the lateral edges thereof, thus insuring a more positive seating of the plane friction surfaces of the friction blocks D.

The central friction block is provided at the inner base thereof with integral lateral extensions 34 underlying the shoulders 35 of the friction box and forming seats against which the outer or forward ends of the side draft springs rest. For providing seats for the concentrically arranged central springs 25 and 26, said center friction block is recessed at its inner face to form adjoining pockets 36 and 37. These pockets are preferably quite deep, permitting increased length and consequent increased capacity of the center springs. This increased capacity may be obtained in a number of different ways, for example, as has been illustrated in the drawings, these springs at the time of their application have been placed under greater initial compression than the side springs. The pocket 37 may be a continuation of the pocket 36, formed in the bottom of the latter so as to provide independent concentric seats for the respective springs. It will be noted that the bottom of these pockets are disposed toward the forward end or apex of the center friction block and abreast of the region of frictional contact between the blocks whereby the reaction of the center springs aids materially in holding this center block in properly aligned position during its forward and backward movements. It will be understood that the inner springs 23 and 25 could if desired be constructed shorter than the respective outer springs 24 and 26, so as to come into action only after a predetermined movement of the central friction block. Such a construc-

tion will offer a smaller degree of resistance for small movements of the gear, and the resistance will be increased after a predetermined movement when the inner springs 5 come into action. It is preferable however in the present embodiment to use all springs of full length for a high initial resistance. As will be clearly seen in Fig. 4, the interior reinforcing and stiffening walls of the 10 spring barrel are discontinued at the mouth thereof and for a considerable distance therebeyond, for providing clearance for the forward movement of the central friction block. The lateral extensions 34 of the central block are preferably slotted, as indicated at 38, for receiving ribs 39 on the interior of the spring barrel. These ribs, which are continuations of the internal walls 15 and 16, in addition to their reinforcing 20 function co-operate with slots 38 for guiding and steadyng the center block in its forward and backward movements. Similar guiding ribs 40 for the center block co-operating similarly with the latter, may also 25 be provided on the interior of the top and bottom walls of the spring barrel. Ribs 40 are preferably integral with the barrel, increasing in width near the inner terminations thereof and merging with the inclined 30 walls 17' and 18', and providing additional reinforcement for the adjacent regions of the spring barrel.

As indicated at D' in Fig. 4, the inner adjacent portions of the side friction blocks 35 D are cut away to form substantially parallel adjacent walls. This construction permits the blocks to move in operation for a considerable distance toward each other without interference, and permits the use 40 of a comparatively narrow center block.

For holding the parts of the draft gear in a self-contained portable unit for application in operative position to a railway car, or the like, or removal therefrom, without 45 use of special tools or apparatus, it is desirable to provide a retaining device or bolt. As shown, this retainer comprises links 41 and 42 anchored respectively in the follower plate E and the bottom 12 of the spring 50 barrel. These links are arranged approximately at the longitudinal center line of the assembly and are loosely articulated to each other by means of the interlinked terminal loops 43, 44. This articulation limits movement of separation of the follower plate E 55 with respect to the spring barrel, but permits these parts to move together by telescoping of the looped portions. The retaining element is conveniently placed in position at the shop, factory or other place 60 where the mechanism may be advantageously assembled, the draft springs being placed under such initial compression as desired, and the gear assembly confined within dimensional limits fixed by standard practice. 65

The self-contained draft gear unit may then be packed and transported with facility, and is readily applied in operative position on the car.

The operation of the improved draft gear 70 in actual practice, and the application thereof to railway cars, being sufficiently indicated in the foregoing detailed description, and will be clearly understood by those skilled in the art without further explanation. 75

As many changes could be made in the above construction and many apparently widely different embodiments of this invention could be made without departing from 80 the scope thereof, it is intended that all matter contained in the above description or shown in the accompanying drawings shall be interpreted as illustrative and not in a limiting sense. 85

It is also to be understood that the language used in the following claims is intended to cover all of the generic and specific features of the invention herein described and all statements of the scope of the invention, 90 which, as a matter of language, might be said to fall therebetween.

Having described my invention, what I claim as new and desire to secure by Letters Patent is: 95

1. In a friction draft gear, in combination, a spring support, a friction box, and a key for securing said box to said support, said key terminating intermediate the walls of the support and being provided with an inner retaining bead. 100

2. In a friction draft gear, in combination, a spring barrel, a friction box adjacent one end of said barrel and having inclined surfaces, friction blocks movable relatively 105 to said box and having inclined friction surfaces adapted for cooperation with said first-mentioned friction surfaces, the friction surfaces of one of said elements being transversely curved the cooperating surfaces of 110 the other of said elements being substantially flat.

3. In a friction draft gear, in combination, a spring barrel, a friction box seated in said spring barrel, said friction box and spring barrel being formed with aligned apertures, and a key seated in said apertures for holding said box and said barrel in assembled relationship, and having a securing extension intermediate the walls of the 120 spring barrel. 115

4. In a friction draft gear, in combination, a spring barrel, a friction box seated upon said barrel and having inclined friction surfaces, friction blocks movable relatively to said box and having inclined friction surfaces adapted for co-operation with said first mentioned friction surfaces, one of said friction surfaces being crowned and the co-operating surface being flat. 125 130

5. In a friction draft gear, in combination, a spring support, a friction box, key-receiving apertures disposed respectively in diagonally opposite corners of each of said support and of said box, the apertures in corresponding corners being adapted to be in register when said support and box are in assembled relation, and keys disposed in retaining members whereby said keys, when in place, are adapted to retain said box and support in assembled relation.
6. The method of securing a friction box to a supporting element of a friction draft gear which is provided with aligned apertures in the box and supporting element and with a space therebetween adjacent said apertures, which comprises forcing a metallic key, while hot, into said apertures and causing the metal of said key to flow laterally therefrom to provide an internal securing projection seated in said space.

In testimony whereof I affix my signature.

ERNEST G. GOODWIN.
